GARMENT RACK

Arthur E. Sanderson, San Pedro, Calif.

Application February 12, 1945, Serial No. 577,504

2 Claims. (Cl. 211—99)

1

This invention relates to a garment rack of the general character embodied in my U. S. Letters Patent No. 1,902,724, issued March 21, 1933, and wherein is disclosed and claimed, a structure by which a large number of garments can be supported and compactly stored in a shallow closet or other restricted space without wrinkling or disarranging the garments, yet enabling the garments to be applied to and removed from the rack with the utmost convenience.

It is the primary object of the present invention to provide a garment rack having all the advantages of the patented rack above set forth, and characterized by a simplified structure wherein the number of parts is greatly reduced without the loss of any functions essential to the operation of the rack in supporting a large number of garments and storing same compactly and smoothly in a relatively small space, while enabling the garments to be conveniently applied to and removed from the rack.

A further object of the present invention is to provide a garment rack of the above described character whose few parts can be cheaply constructed by quantity production methods from sheet metal, and simply assembled to form a rack of such structural strength and engineering design, that when properly installed on a suitable support, the rack will be extremely rigid under a load of garments, yet can be readily manipulated to occupy a raised position for the application and removal of garments, or a lowered position to compactly store the garments.

With these and other objects in view, the invention resides in the combinations, arrangements and functional relationships of elements as set forth in the following specification and particularly pointed out in the appended claims.

In the accompanying drawing,

Figure 1 is a view of the garment rack in side elevation, and installed in a shallow closet or similar restricted space;

Figure 2 is an enlarged plan view of the rack;

Figure 3 is an enlarged side view partly broken away, showing the rack sustained in its raised position for the application and removal of garments;

Figure 4 is a detail sectional view taken on the line 4—4 of Figure 3;

Figure 5 is a fragmentary view similar to Figure 3 and illustrating the rack released for lowering movement; and

Figure 6 is a view similar to Figure 5, but with the rack lowered to compactly store the garments carried thereby.

2

Referring specifically to the drawing, the invention in its illustrated embodiment comprises a bracket designated generally at B and constructed of sheet metal to provide a rectangular attaching plate 10 from one vertical edge of which projects at a right angle, a bearing or cheek plate 11 which has an extension along its upper horizontal edge return bent downwardly and parallel to the plate so as to provide a second bearing or cheek plate 12.

The plates 11 and 12 are in spaced relation to provide therebetween a guide channel 14 closed only at the top to provide along the length of the latter a fixed abutment 15.

Co-acting with the bracket B is a garment supporting member designated generally at S. This member is also constructed from sheet metal of suitable gage to insure rigidity, and is of L-shaped cross section to provide a relatively long arm having a vertical flange 20 co-extensive in length with the arm, and a horizontal flange 21 extending along the upper edge of the vertical flange. The horizontal flange terminates in spaced relation to the inner end of the arm by being return bent against the vertical flange as indicated by 22, with the combined thicknesses of the flanges enabling the inner end portion of the arm to be closely received in the guide channel 14.

The cheek plates 11 and 12 are provided with registering openings 25 and 26, whereas the vertical flange 20 of the supporting member S is provided adjacent its inner end with a horizontal slot 27, through all of which passes a pivot pin 28 which may be in the form of a rivet or other suitable fastening member. By means of the pin 28 and slot 27, the supporting member S is thus mounted on the bracket B for various manipulations. With the attaching plate 10 secured by screws 30 or other fastening members to a rigid support such as a wall W, the pin and slot co-act to mount the supporting member for translatory movement horizontally which is parallel to the length of the bracket, to occupy the extreme position shown in Figure 3, or the extreme position shown in Figure 5, to accordingly sustain the member raised, or release it for pivotal lowering movement about the axis of the pin, as will be later fully described.

At intervals along its length, the flange 20 of the supporting member S is provided with vertically elongated openings 31 through which the hooks of conventional garment hangers are adapted to be hooked to suspend garments from

the member in the operation of the invention which is as follows:

Let it be assumed that the garment rack is installed on the wall W which is shown as the rear wall of a closet C whose depth from its door D is so shallow as to be incapable of receiving the length of the supporting member S when occupying its raised position as shown in broken lines in Figure 1.

With the supporting member occupying the extreme position of translatory movement horizontally as shown in Figure 3, the pin 28 will be disposed at the inner end of the slot 27 so that the portion of the member between its inner end and the axis of the pin will constitute a lever arm a of such length, that under the weight of the member and the load of garments carried thereby, the lever arm will be forced upwardly to bear tightly against the fixed abutment 15 formed by the closed top of the channel 14. Thus, the member S will be locked in its raised position by its binding action upon the bracket B, so that garments carried by the hangers can be conveniently applied to and removed from the supporting member.

However, upon effecting translatory movement of the supporting member to its other extreme position shown in Figure 5, the pin 28 will be disposed at the outer end of the slot, thus shortening the length of the lever arm a sufficiently for it to be incapable of engaging the fixed abutment 15, with the result that the supporting member will be free to gravitate about the axis of the pin 28 to the lowered position shown in Figure 6 and in full lines in Figure 1. The suspended garments will now be compactly stored smoothly one against another by the rack, with the supporting member entirely disposed within the shallow depth of the closet C so as to permit the door D to be closed.

As the pivoted end portion of the supporting member S is closely confined between the bearing or cheek plates 11 and 12 of the bracket B, and slides during its translatory movement in close relationship to the surface of the bracket defining the fixed abutment 15, the member will be rigidly sustained in its locked raised position, yet can be easily manipulated for translatory movement to its released raised position by merely exerting a slight upward pressure upon the outer or free end of the member as such translatory movement of the member is being effected, thus enabling the member to be lowered with the utmost ease. It will be clear that the supporting member can be as easily raised and restored to locked position by reversing the above described operation, so as to render the stored garments accessible for removal from the rack, or enable

garments to be applied to the rack, as the case may be.

It will be manifest that the essential functions as above described result from a simple construction and arrangement of elements which lend themselves to cheap, quantity production, so that the garment rack can be manufactured and sold at a lower cost than racks of this type heretofore proposed.

I claim:

1. A garment rack comprising: a sheet metal bracket including an attaching plate having a vertical cheek plate projecting at an angle therefrom said cheek plate provided along its upper edge with an extension return bent downwardly in spaced parallel relation to said cheek plate to provide a second cheek plate; a sheet metal supporting arm of inverted L-shaped cross section providing a vertical flange and a horizontal flange terminating in spaced relation to one end of the arm by being return bent at said end over the vertical flange to reinforce the latter; said vertical flange having a slot therein adjacent said one end of the arm and whose length extends in the direction of the length of the arm; and a pin mounted in said cheek plates and passing through said slot to mount the arm between said cheek plates for translation from one extreme horizontal position or another, to accordingly cause said one end of the arm to engage said return bend of the cheek plates for co-action therewith in sustaining the arm elevated, or to free said one end of the arm from such return bend for lowering movement of the arm about the axis of said pin.

2. A garment rack comprising: a sheet metal bracket including an attaching plate having angularly disposed cheek plates in spaced parallel relation and connected across the top thereof to provide a fixed abutment surface; a sheet metal garment supporting arm of inverted L-shaped cross section providing a vertical flange and a horizontal flange return bent upon the vertical flange along one end portion of the arm; said end portion of the arm being closely received between said cheek plates and having a slot whose length extends longitudinally of the arm; and a pin mounted in the cheek plates and passing through said slot; said end portion of the arm co-acting with said fixed abutment to sustain the arm against lowering movement when the arm is longitudinally adjusted to dispose the pin at the inner end of the slot; and to be clear of the abutment when the arm is longitudinally adjusted to dispose the pin at the other end of the slot, so that the arm will be free to gravitate about the axis of the pin.

3. A garment rack comprising: a sheet metal bracket including an attaching plate having a vertical cheek plate projecting at an angle therefrom said cheek plate provided along its upper edge with an extension return bent downwardly in spaced parallel relation to said cheek plate to provide a second cheek plate; a sheet metal supporting arm of inverted L-shaped cross section providing a vertical flange and a horizontal flange terminating in spaced relation to one end of the arm by being return bent at said end over the vertical flange to reinforce the latter; said vertical flange having a slot therein adjacent said one end of the arm and whose length extends in the direction of the length of the arm; and a pin mounted in said cheek plates and passing through said slot to mount the arm between said cheek plates for translation from one extreme horizontal position or another, to accordingly cause said one end of the arm to engage said return bend of the cheek plates for co-action therewith in sustaining the arm elevated, or to free said one end of the arm from such return bend for lowering movement of the arm about the axis of said pin.

4. A garment rack comprising: a sheet metal bracket including an attaching plate having angularly disposed cheek plates in spaced parallel relation and connected across the top thereof to provide a fixed abutment surface; a sheet metal garment supporting arm of inverted L-shaped cross section providing a vertical flange and a horizontal flange return bent upon the vertical flange along one end portion of the arm; said end portion of the arm being closely received between said cheek plates and having a slot whose length extends longitudinally of the arm; and a pin mounted in the cheek plates and passing through said slot; said end portion of the arm co-acting with said fixed abutment to sustain the arm against lowering movement when the arm is longitudinally adjusted to dispose the pin at the inner end of the slot; and to be clear of the abutment when the arm is longitudinally adjusted to dispose the pin at the other end of the slot, so that the arm will be free to gravitate about the axis of the pin.

ARTHUR E. SANDERSON.
